UNITED STATES PATENT OFFICE

158,249

BOBBY PIN OPENER

Roland S. Claflin, Park Ridge, Ill.

Application February 28, 1948, Serial No. 144,800

Term of patent 14 years

(Cl. D86—10)

To all whom it may concern:

Be it known that I, Roland S. Claflin, a citizen of the United States, residing at Park Ridge, Illinois, have invented a new, original, and ornamental Design for Bobby Pin Opener, of which the following is a specification, reference being had to the accompanying drawing, forming part thereof.

Figure 1 is a perspective view of a bobby pin opener, showing my new design;

Figure 2 is a bottom plan view of the bobby pin opener;

Figure 3 is a top plan view of the bobby pin opener;

Figure 4 is a side view of the bobby pin opener; and

Figure 5 is an end view of the bobby pin opener.

I claim:

The ornamental design for a bobby pin opener, as shown.

ROLAND S. CLAFLIN.
